UNITED STATES PATENT OFFICE.

HARRY G. RUSSELL, OF BATTLE CREEK, MICHIGAN, ASSIGNOR TO CONSOLIDATED ELECTRIC SIGN CORPORATION, OF BATTLE CREEK, MICHIGAN.

DESIGN FOR A SIGN.

Application filed July 28, 1927. Serial No. 22,901. Term of patent 3½ years.

To all whom it may concern:

Be it known that I, HARRY G. RUSSELL, a citizen of the United States, residing at Battle Creek, in the county of Calhoun and State of Michigan, have invented a new, original, and ornamental Design for Signs, of which the following is a specification, reference being had to the accompanying drawing, forming a part thereof, in which—

Fig. 1 is a front view, and

Fig. 2 is a side view of a sign showing my new design.

I claim:

The ornamental design for a sign, as shown.

HARRY G. RUSSELL.
